UNITED STATES PATENT OFFICE.

HAROLD A. MESSERVY, OF TORONTO, ONTARIO, CANADA.

COIN-CONTROLLED APPARATUS.

Original application filed December 8, 1923, Serial No. 679,292, and in Canada December 4, 1923. Divided and this application filed August 19, 1924. Serial No. 732,909.

My invention relates to a coin-controlled apparatus, especially devised to be used in connection with a liquid dispenser, the present application being a division of my 5 pending application, Serial Number 679,292, filed December 8th, 1923, for a coin-controlled liquid dispenser.

The object of my invention is to enable the dispensing of the liquid by the insertion of coins of different values.

A further object is to so dispose the coin-operated mechanism that it will simultaneously control the filling of the dispensing tank as well as the emptying of the same.

In the accompanying drawings forming part of the following description:

Figure 1 is a sectional elevation of part of a gasoline dispenser wherein the coin-controlled operating mechanism is mounted;

Figure 2 is a top view of the controlling disk taken on line 2—2, Figure 1;

Figure 3 is a horizontal section of the operating disk taken on line 3—3, Figure 1;

Figure 4 is a sectional elevation on line 25 4—4, Figure 1;

Figure 5 is a section through one of the coin slots;

Figure 6 is a section on line 6—6, Figure 5; and

Figure 7 is a detail of the disk-locking mechanism;

Figure 8 is a detail of a part of the disk-retaining mechanism.

Referring to Figure 1, 10 is a section of a standard surrounding a tube (not shown) intended to convey liquid to a measuring reservoir. Upon the standard 10 is mounted a coin trunk 11. Below this coin trunk, a disk 12 is mounted to rotate around the stand pipe 10. The disk is provided with a deep groove 13 into which is mounted to rotate an operating lever 14, said lever being mounted at the bottom of the groove preferably by a separate collar 15, united

45 by means of bolts 16. Lever 14 extends outside the standard 10 and travels into a slot 17 in a casing 18, which casing is mounted in a groove 19 formed in the coin trunk 11. Lever 14 is provided with a hand piece 20, as shown.

In order to cause lever 14 to retract independently of disk 12, I provide a spring 21 (see Figure 3). This spring is shown con-

nected to the head of one of the bolts 16 and to a hook 22 on the inside of casing 18. 55

So far, it has been said that the disk 12 rotates about the standard 10 and that lever 14 rotates about the disk 12. In order to rotate the disk 12 by means of lever 14, it is necessary to provide a means of tem-

porarily locking the same to effect this rotation. This is done by means of coins of several denominations, two of which are shown in the present instance at 23 (see

Figure 4). These coins are of respective 65 values of twenty-five and fifty cents. The coins are introduced in slots 25 and 26 in the coin trunk 11, which coin trunk, as

previously stated, is fastened to the standard 10 by means of set screws 24 and forms 70 part of a circular flange extending outside casing 18. It will be noticed that the

twenty-five-cent slot 25 is set in advance of the fifty-cent slot 26 a space equal to the difference in value of the liquid dispensed. 75 The coin slots are curved as shown in Figure 5.

So as to prevent the insertion of a coin of different denomination than that intended for the particular slot, I form under-

neath the curve a chamber 25^a, having an opening into the coin slot 25, the coin slot being provided with guiding grooves 25^b positioned over the opening. Whenever a

coin of proper denomination is inserted into 85 the opening 25^a, it will engage the grooves 25^b in the coin slot 25 and follow the same over chamber 25^a until it reaches the slot in the disk 12. Should a coin of smaller

diameter than the one intended for the particular slot be inserted, it will drop into the chamber 25^a as its diameter will be less than that required to keep it within the grooves 25^b. The chamber 25^a communicates outside the standard so that the wrong coin 95 may be returned to its owner.

The locking of lever 14 to the disk 12 is accomplished by the face of the coin in the following manner: When a coin is inserted in slot 25, it falls down into a slot 100 27 in the disk 12 and when a fifty-cent coin is dropped into slot 26, it will fall into a corresponding slot 28, also in disk 12. It should be understood, of course, that there are opposite the twenty-five cent slot 25, six 105 slots disposed around disk 12, making a to-

tal of one dollar and fifty cents' worth of liquid dispensed, and that there will be five slots in the same disk opposite the fifty-cent slot 26. It may be remarked that the 5 coin slots in disk 12 extend on both sides of groove 13 and as the thickness of this groove is less than the diameter of the coins inserted, they will project on both sides of the lever 14 and rest against the 10 walls of the slot in the disk, thereby locking lever 14 to the disk 12 until such time as they drop into the coin box 29, which box may also be fastened to the standard 10 by means of set screws 30. It will be 15 understood, of course, that when the lever has travelled the whole path, the coin will drop into the coin box through a slot 32.

In order to prevent the coin inserted in disk 12 from being retracted, means are 20 provided to hold the coin until it reaches the end of the travel of the disk. For that purpose, I provide pawls 33 and 34 (see Figure 4), pawls 33 being mounted in cavities 35 in the coin trunk 11 and pawls 34 25 being mounted in similar cavities 36 formed around the coin box 29. It will be understood that there is a set of pawls back of every slot in the coin box. Each pawl is provided with a spring 37 to keep the 30 same against the face of disk 12. Back of each slot in the disk is formed depressions 38 to allow the pawls to fall behind the coin whenever the disk is in position to receive them. As the pawls rest in the 35 disk, the back face of the coin will be retained by them and the disk so that the coin cannot be moved backward on the retraction of lever 14.

As soon as the coin falls into the coin 40 box, the disk 12 is disengaged from the lever but it is essential that the disk will remain in position until the liquid purchased is fully dispensed. For that purpose, it becomes necessary to temporarily lock disk 45 14 by some means, which in the present instance comprises the following arrangement: A number of depressions 39 (see Figures 2 and 7) are made in the face of disk 12, into which a pawl 40, fulcrumed on the 50 trunk 11, enters. These depressions are so shaped to allow the pawl to disengage itself when free from pressure. Therefore, in order to hold them in pressed engagement, I provide a rod 41 passing through 55 a perforation 42 in the coin trunk 11 and connected to a lever 43 fulcrumed at 44 (see Figure 8), which lever extends over the outlet 45 where it is connected to a rod 46 supporting a cup (not shown) positioned 60 in the path of the liquid flow. The cup is provided with a perforation sufficiently large to drain the liquid contained therein after the flow ceases. Whenever the cup is filled with liquid, its weight will depress lever 65 43 and forces rod 41 on pawl 40 to main-

tain the same in locked position. The moment the cup is empty, rod 41 will be released and pawl 40 will easily be disengaged from the depression 39, and the disk being now freed, will retract to its normal 70 position by means of spring 47 connected at 48 to collar 49 fixed to disk 12 and to the coin trunk 11 at 50. It will thus be seen that lever 14 can only operate disk 12 when a coin is inserted in either of the 75 slots mentioned.

The mechanism to which this coin slot is applied is fully described in my co-pending application above referred to but in order to fully understand its working in relation therewith, I have shown in Figure 1 a section of a valve-opening rod 51, resting on disk 12. This rod is actuated vertically by means of a cam 52, circularly mounted on disk 12 so that when the same 80 is rotated, it will engage the end of rods 51 and raise the same to open a valve (not shown), intended to draw the liquid purchased.

To obtain liquid, the purchaser inserts a 85 coin of either a twenty-five or fifty cent value. The twenty-five cent coin is inserted in a slot 25, which is positioned midway of the travel of the lever 20. In such a case, the lever 20 moves freely from its resting 90 point to opposite the slot 25, when its free path is obstructed by the coin in that slot which has dropped into the disk carrying cam 52, which operates the valve rod 51. Consequently, the twenty-five cent piece will 95 cause the cam to raise the valve of the tube in the gasoline container delivering a twenty-five cent value. When a fifty-cent piece is used, it is dropped into the slot 26, which is positioned a distance back of slot 25 100 equal to the value of the distance of travel for the delivery of a twenty-five cent value. The fifty-cent piece, consequently, locks the lever 20 immediately at its resting point and when this lever is operated, it will travel double the distance of that of the twenty-five cent value. Consequently, fifty-cents' 105 worth of liquid will be dispensed. In Figure 3 the position of slots 27 and 28 are indicated and as the opening for the twenty-five cent slot is just equal to the diameter of the coin, it will be impossible to insert a fifty-cent piece there and vice versa for the fifty-cent slot as its diameter is too great 110 to adapt the twenty-five cent piece which 115 when falling into the disk would not lock the lever. It will be understood that the groove in disk 12 is wider opposite the fifty-cent slot than it is opposite the twenty-five cent slot. The moment the lever has reached the limit of its travel, the coin will drop into a coin box. The disk, being then free, will return to its original position, when a repetition of the operation above described 120 may be made.

What I claim is:—

1. In a coin-controlled apparatus of the class described, a standard, a stand pipe mounted therein, a trunk box around said standard, a coin box also mounted on said standard below said trunk box, a disk revolvably mounted on said standard between the coin trunk and coin box, a lever mounted to rotate in said disk independently of the same, coin slots in said disks coinciding with slots in the coin trunk so as to lock said lever by means of coins inserted through said coin trunk in said disk.
2. In a coin-controlled apparatus of the class described, a standard, a trunk box mounted on said standard, a coin box also mounted on said standard below said trunk box, a disk rotatably mounted on said standard between the coin trunk and coin box, a deep groove in the edge of said disk, a lever mounted to rotate in said groove independently of the disk, coin slots around the face of said disk, coinciding with slots in the coin trunk, means to retract said lever, means to retract said disk, means to lock said lever to said disk, comprising coins inserted through the slots of the coin trunk into one of the slots in the disk, the said lever being free when the coin reaches the slot in the coin box and falls therein.
3. In a coin-controlled apparatus of the class described, a standard, a stand pipe mounted therein, actuating rods, a rotary disk mounted horizontally under said rods, a cam positioned to engage said rods gradually as the disk is revolved, a coin trunk mounted over said disk, coin slots in said trunk, a coin box mounted under said disk, coin slots in said disk coinciding with the slots in the coin trunk, a coin slot in the coin box coinciding with the slots in the disk, said coins locking a lever to the disk so as to rotate said disc, means to lock the disk until the liquid being dispensed is totally discharged, and means to prevent the coins from being taken out from the disk once they are inserted therein.
4. In a coin-controlled apparatus of the class described, a standard, a coin trunk mounted around the same, coin slots adapted to receive coins of various denominations, said coin slots being curved to prevent other coins than that intended to travel therein from being used, a coin disk mounted to rotate underneath said coin box, having coin slots around the same coinciding with the coin slots in the coin trunk, a groove in said disk, a lever rotatably mounted in said groove, a coin box underneath said disk having an opening to receive the coins dropped from said disk, cavities in the upper face of said disk adjacent one of the walls of said coin slots therein, pawls yieldingly mounted on the coin box, positioned to enter said cavities in the upper face of said disk adjacent one of the walls of said coin slots, pawls yieldingly mounted in the coin box, positioned to engage the cavities in said under face of said disk adjacent the same wall of said coin slot, said pawls being intended to rest against the coin in said slot and prevent the said disk from rotating backwards, means to lock the disk until the liquid being dispensed is totally discharged, and means to retract said disk when the liquid has been totally dispensed.
5. In a dispenser of the class described, a dispensing container, means to deliver a predetermined quantity of liquid therefrom proportionate to the coins inserted, means to actuate said first means comprising a rotating disk, coin slots in said disk, a lever for actuating said disk locked to the same by means of the coins inserted in said slots, means to prevent the said coins from being withdrawn, pawls positioned on both sides of said disk and engaging depressions back of the coin slots to prevent the disk from being retracted until the coin has been discharged.

In testimony whereof, I have hereunto affixed my signature, this 22nd day of July, 1924, at the city of Charlottetown, Canada.

HAROLD A. MESSERVY.
